CLAIM

The ornamental design for a display screen or portion
thereof with graphical user interface, as shown and
described.

DESCRIPTION

The file of this patent contains at least one drawing/photograph
executed in color. Copies of this patent with color
drawing(s)/photograph(s) will be provided by the Office
upon request and payment of the necessary fee.

The sole FIGURE shows a display screen or portion thereof
with graphical user interface showing our new design.

The peripheral dashed broken lines illustrate a display
screen or portion thereof, which forms no part of the claimed
design. The interior broken lines illustrate portions of the
graphical user interface which form no part of the claimed
design.
